UNITED STATES PATENT OFFICE.

LEVIN FAUST AND FRANK W. LINDGREN, OF ROCKFORD, ILLINOIS.

MORTISING-MACHINE.

SPECIFICATION forming part of Letters Patent No. 642,313, dated January 30, 1900.

Application filed August 19, 1899. Serial No. 727,748. (No model.)

To all whom it may concern:

Be it known that we, LEVIN FAUST and FRANK W. LINDGREN, citizens of the United States of America, residing at Rockford, in the county of Winnebago and State of Illinois, have invented certain new and useful Improvements in Mortising - Machines, of which the following is a specification.

Our invention relates specifically to a machine for cutting mortises for the reception of the leaves of hinges; and it consists of certain new and useful features of construction and combinations of parts hereinafter fully described, and specifically pointed out in the claim.

Referring to the accompanying drawings, which form a part of this specification, Figure 1 is a side elevation of a mortising-machine embodying our improvements. Figure 2 is a like view of the same with one-half of its frame sectioned away through the dotted line 2 2 in Fig. 3. Fig. 3 is a top plan view of the machine. Figs. 4 and 5 are detailed views of the mortising-chisels of the same. Figs. 6 and 7 are views of pieces of wood having mortises cut thereinto by our improved mortising-machine.

Like letters of reference indicate corresponding parts throughout the several views.

A is the frame of the mortising-machine and is composed of a base A' and a vertical column A², having a vertical central opening A³, Fig. 2, extending the entire length thereof, and is integral.

B B' are respectively vertical and horizontal chisel-stock slideways, the former formed in and the latter rigidly secured to the frame A.

C is a vertically-reciprocating chisel-stock adapted to slide in the vertical slideway B and provided with a chisel C' of any desired form, here shown as being three-sided and rectangular.

D is a horizontally - reciprocating chisel-stock, adapted to slide in the horizontal slideway B and provided with a chisel D' of any desired form, here shown as being flat and of the ordinary form.

E is a bar connection pivoted by one end E' to the vertically-reciprocating chisel-stock

C by means of a pintle E² and by the other end E³ to the horizontally - reciprocating chisel-

stock D through the head E⁴, fast thereto by means of a pintle E⁵.

F is a shaft provided with a driving-pulley F' and mounted in horizontal bearings F², 55 supported by the base A' of the frame A.

G is an eccentric fast to the shaft F.

H is an eccentric-rod pivoted by one end H', Fig. 2, to the vertically - reciprocating chisel-stock C by means of the pintle H² and 60 connected by the other end H³ through the eccentric-hoop H⁴ with the periphery of the eccentric G.

I is an eccentric mounted on a horizontal bearing I' on the column A² of the frame A 65 and provided with an operating-lever I².

J is the bed-piece of a vertically-reciprocating carriage, now to be described, and is provided with an operating-arm J', projecting upward therefrom and at its upperend J² 70 into engagement with the periphery of the eccentric I whereon it rests and whereby the entire carriage is suspended.

J³ is the upper portion of the carriage, of which J is the bed-piece, and is vertically adjustable on the latter by means of the screw J⁴, which passes upward therethrough into a socket J⁵ in the former. The carriage, consisting of the parts J J³, is also provided with an inclinably-adjustable clamping-vise J⁶. 80 The latter consists of a horizontal leaf-like portion K, capable of being inclined downward on its hinge-joint K' until it is in a vertical position, having a series of depressions K² in the upper face thereof, terminating at 85 its inner end in a wide vertical jaw K³, furnished with a slotted arm K⁴, pivot-jointed at K⁵ thereto, and a set-screw K⁶ passed through the slot K⁷ therein to clamp the same to the rigid lug K⁸ on the part J³ and provided with 90 a sliding clamping-jaw K⁹ and a sliding set-screw carriage K¹⁰, having a locking-pawl K¹¹ and a set-screw K¹² for setting the jaw K⁹ against any piece of wood, as L, to secure the same against the jaw K³ for the purpose of 95 having a hinge-mortise L', Figs. 6 and 7, cut thereinto.

M are gage-rods projecting from the jaw K³ of the clamping-vise J⁶.

M' are gages capable of being secured at 100 any desired points along the rods M by means of set-screws M².

N is a vertical gage adjustable by means of the thread N' thereon and the corresponding thread in the hole N² in the frame A, wherein it turns.

5 The hinge-stiles L of the various house-doors, bookcase-doors, &c., that require to be mortised for the reception of hinge-leaves, will obviously vary much in thickness. By means of the set-screw J⁴ the upper part J³ 10 of the vertically-reciprocating carriage may be readily and accurately adjusted to receive stiles of any desired thickness. The leaves of hinges for which mortises are to be cut will also vary in thickness. The vertical gage N 15 by being turned up or down accurately regulates the depth of mortises L' to be cut.

In cabinet and some other classes of work it frequently becomes necessary to cut mortises on stile edges that form acute or obtuse 20 angles with the faces of such stiles. The clamping-vise J⁶ is made inclinably adjustable to adapt the machine to cut mortises into such stile edges.

The set-screw carriage K¹⁰ may be so set by 25 means of depressions K² in the parts K and the locking-pawl K¹¹ as to adapt the machine to receive and cut mortises into stiles of any desired width.

Our machine is operated as follows: Place 30 a stile L on the leaf K of the clamping-vise J⁶ against the jaw K³. Next advance the jaw K⁹ against it. Then turn the set-screw K¹² until the stile is securely clamped therein.

Adjust the part J³ of the vertically-reciprocating carriage and set the gage N, all as 35 hereinbefore indicated, and supposing the driving-shaft F to be in rotation press upon the lever I⁸, which, acting upon the eccentric I, will, through the operating-arm J', elevate the carriage until the chisels have cut a mortise L' to the depth required, as determined by the gage N.

We claim as new and desire to secure by Letters Patent—

In a mortising-machine, in combination, a 45 frame, a vertically-reciprocating chisel-stock, with its chisel, mounted therein, a horizontally - reciprocating chisel - stock, with its chisel, mounted therein, a bar connection pivoted, by one end, to the vertically-reciprocating chisel-stock, and by the other end, to the horizontally - reciprocating chisel - stock, an eccentric and its driving-shaft, an eccentric-rod, pivoted, by one end, to the vertically-reciprocating chisel-stock, and connected, by 50 the other end, with the eccentric, substantially as and for the purpose specified.

In testimony whereof we have signed our names to this specification in the presence of two subscribing witnesses.

LEVIN FAUST.
FRANK W. LINDGREN.
